(57) **CLAIM**

The ornamental design for a battery pack for a camera, as shown and described.

DESCRIPTION

FIG. 1 is a perspective view showing an embodiment of a battery pack for a camera that is our novel design as seen obliquely from the front upper left side thereof;

FIG. 2 is a perspective view as seen obliquely from the rear lower left side thereof;

FIG. 3 is a front view thereof;

FIG. 4 is a rear view thereof;

FIG. 5 is a plan view thereof;

FIG. 6 is a bottom plan view thereof;

FIG. 7 is a right side view thereof;

FIG. 8 is a left side view thereof;

FIG. 9 is a perspective view for reference showing the state of having mounted the battery pack for a camera of the embodiment to a camera body as seen obliquely from the rear lower left side thereof, in which the portion indicated by solid lines is the one for which the right as the design invention is sought while the portion indicated by dotted lines is not the one for which the right as the design invention is sought; and,

FIG. 10 is a perspective view for reference as seen obliquely from the front upper left side thereof, in which the portion indicated by solid lines is the one for which the right as the design invention is sought while the portion indicated by dotted lines is not the one for which the right as the design invention is sought.

The broken lines showing the camera body are included for the purpose of illustrating environmental structure and form no part of the claimed design.
